TOP STOP FOR SEPARABLE FASTENERS

Joseph Léon Larroque, Rouen, France, assignor
to Hookless Fastener Company, a corporation
of Pennsylvania

Application November 27, 1935, Serial No. 51,870
In Great Britain November 21, 1934

5 Claims. (CL 24—205)

This invention relates to sliding clasp fasteners of the kind comprising two flexible stringers having fastener members mounted thereon and adapted to be interlocked and disengaged by the action of a slider. The invention relates in particular to means for binding the ends of the said flexible stringers. The invention relates moreover to garments or articles incorporating fasteners of the kind described in which elastic insertions are provided in the flexible stringer tapes.

These portions of the fastener stringers are usually terminated by folding over the tape adjacent to the end stops in order to conceal the frayed edges of the tape when the fastener is sewn on to a garment or article. The folding over of the tape, however, tends to make the fastener stringers bulky at the extremity and this is particularly so when special tapes having elastic insertions are used.

One object of my invention is to provide means whereby the ends of the fastener stringers are bound in a neat and effective manner and whereby the frayed edges of the mounting tape are completely concealed.

Another object of the invention is to provide an end binding for fastener stringers which are elastic in the cross-wise direction wherein the binding is also stretchable in the crosswise direction.

According to the present invention, in sliding clasp fasteners of the kind described, the flexible stringers are provided with a smooth and coherent end binding or border of non-metallic plastic material, for example rubber, which is molded, stuck or otherwise affixed in position on the end of the said stringers. The arrangement is preferably such that part of the binding material forms the end stop of the fastener and this portion, may, if desired, be hardened or toughened while the remainder of the material is made substantially flexible.

The invention may be applied, if desired, not only to the separable ends of the fastener, but also to the remote ends which are not adapted to be separated in the normal use of the fastener or the article to which it is attached.

The plastic material which forms the end binding of the present invention is preferably a rubber composition but may also comprise a synthetic resin preferably of the thermoplastic type. Thermo hardening resins may also be employed provided that the hardening operation is so conducted that the tape is not thereby damaged.

The invention will now be described by way of illustration with reference to the accompanying drawing in which—

Fig. 1 shows a perspective view of a shoe fitted with a fastener constructed in accordance with the present invention;

Fig. 2 is a front view on an enlarged scale of the top end of the fastener constructed in accordance with my invention, the upper end of the fastener being shown in a stretched condition;

Fig. 3 is a detail view showing the end of one of the tape stringers;

Figs. 4 and 5 are cross-sections on lines 4—4 and 5—5 respectively of Fig. 3; and

Fig. 6 is a perspective view of a modified form of the invention.

In these figures, a shoe 1 is fitted with a sliding, clasp fastener 2 comprising two flexible stringers 3, on the edges of which are mounted series of interlocking fastener members 4. In order to ensure that the front of the shoe will fit closely to the foot with a maximum degree of comfort, the fastener tapes are provided with insertions of elastic material 5 which are woven into the non-stretching portions 6 of the tapes. By this means a certain amount of cross-wise stretching of the front portion of the shoe is provided when the fastener is in the closed position.

Each upper or separable end of the fastener is provided with an end binding consisting of a piece of rubber or like material 7, which is molded in position as shown. The rubber molding which completely embraces the end of the tape including the elastic portion 5, firmly holds the cotton and elastic threads of the insert together and permits the end of the fastener stringer to be finished off squarely and smoothly without any rough edges. Part of the border 8 adjacent to the cored edge of the tape is adapted to act as the top end stop of the fastener, to prevent the removal of the operating slider 9. This portion is suitably thickened as shown, and is preferably toughened or hardened to resist wear. Preferably also the piece of rubber has a rib 10 extending across the tape so as to reinforce the same and provide a secure stop for the slider. The binding is preferably made thin as indicated at 11 at the edge of the stringer opposite the fastener members, in order that it may more easily stretch. In the central portion the binding material need not cover the elastic insert 5.

The fastener is attached to the front portion of the shoe by means of rows of stitches 12 in the manner shown in Figure 1. It will be observed

that the ends of the fastener stringers are sewn directly to the leather without having to fold over the ends of the tapes as is the usual practice. By this means the difficulty of concealing the folded over ends of the tapes is overcome and the bulky appearance due to this folded construction is avoided. Moreover, since the usual unsightly metal end stops are eliminated, a fastener of much neater appearance than hitherto is produced.

10 The modification shown in Fig. 6 consists of a piece of elastic tape 12 folded over the end of the tape stringer 3 and secured in place in any suitable manner such as by stitching or cement. 15 In this instance a metal stop member 13 is preferably used.

10 It will readily be seen that with either of the constructions shown the upper end of the fastener while securely bound to provide the proper kind 20 of end finish, may yet readily stretch to accommodate the foot of the wearer as in a shoe. The stretching is clearly illustrated in Fig. 2.

15 While I have shown and described in this application two embodiments which my invention 25 may assume in practice, it will be understood that these embodiments are merely for the purpose of illustration and description and that various other forms may be devised within the scope of my invention as defined in the appended 30 claims.

What I claim as my invention is:

1. In a separable fastener of the class described, the combination with a pair of flexible 35 stringers each of which is elastic in the cross-wise direction, a series of fastener members secured to one edge of each of said stringers, and a slider on said fastener members for engaging

and disengaging the same, of an end binding covering one end of the stringer, said end binding also being elastic in the cross-wise direction of the fastener.

2. In a separable fastener of the class described 5 wherein said end binding comprises a piece of elastic fabric folded over the end of the stringer and firmly attached in position thereon.

3. A separable fastener of the class described 10 comprising the combination with a pair of fabric tape stringers, cooperating series of fastener members secured along adjacent edges of the stringers, and a molded rubber stop member secured to and extending transversely of one of 15 the stringers at one end thereof.

4. A separable fastener of the class described comprising the combination with a pair of fabric 20 tape stringers, cooperating series of fastener members secured along the adjacent edges of the stringers, and molded rubber top stop members intimately bonded with and extending across the upper end of the stringers.

5. A separable fastener of the class described, comprising in combination with a pair of fabric 25 tape stringers, cooperating series of fastener members secured along adjacent edges of the stringers, and molded rubber top stop members one on the upper end of each stringer, each of 30 the top stop members comprising a rubber mass having a border portion adapted to enter the slider, a transversely extending portion adjacent thereto of lesser thickness, and a transversely extending rib portion extending across the top of 35 the member to reinforce the same.

JOSEPH LÉON LARROQUE.
